UNITED STATES PATENT OFFICE

WILLIAM S. CARTER, OF NEW YORK, N. Y.

FOLDING TILT DISPLAY CONTAINER

Application filed November 30, 1927. Serial No. 236,788.

The present invention relates to containers or boxes formed by folding and more particularly to display containers formed by folding, and a principal object of the invention is to provide a foldably formed closable container for shipping or storing articles therein and which is foldably convertible from a closed container into a display container of substantially cabinet form supported at an inclination and adapted for effectively and attractively displaying the articles contained therein.

I attain this object, and such other objects as may later appear herein, by the invention 15 one embodiment of which is described by way of example in the subjoined specification and illustrated in the drawings accompanying the specification, and while herein details of the invention are described, it should be understood that I do not restrict myself to such details, but that I may make such variations in 20 and modifications of the invention as do not depart from the spirit of the invention or exceed the scope of the appended claims.

25 In the drawings, Fig. 1 is a perspective front view of the container in folded display form.

Fig. 2 is a rear view of the container in folded display form.

30 Fig. 3 is a front view of the container in folded closed form.

Fig. 4 is a sectional view on the line 4—4 of Fig. 3.

Fig. 5 is a fragmentary perspective sectional view on the line 5—5 of Fig. 1, and

35 Fig. 6 is an extended view of the blank for forming the container.

Briefly stated the container consists of the display portion generally denoted by A, Fig. 1, the pocket portion generally denoted by B, and the easel back generally denoted by C. The display portion includes a display back provided with a closure flap at one end thereof and a display panel on each side thereof, 45 the pocket portion being disposed at the end of the display back opposite said flap and the easel back being disposed on the pocket portion, the container when in display position being of cabinet form.

50 Referring to Fig. 6, the blank for forming

the container by folding the blank on the score lines and cuts thereof is of the irregular shape shown in the drawing and comprises the display back section 10, the panel connecting side sections 11 and 12, the panel sections 13 and 14, the top closure flap 15, the inner rear wall section 16 of the pocket, the inner end wall sections 17 and 18 of the pocket, the bottom section 19 of the pocket, the end closure tabs 20 and 21 of the pocket, 55 the inner front wall section 22 of the pocket, the outer front wall section 23 of the pocket, the outer end wall sections 24 and 25 of the pocket, the section 25 having the locking tab 26 thereon, the outer rear wall section 27 of 60 the pocket having the locking tab 28, the brace section 29 of the easel, the base section 30 of the easel, and the easel tuck 31.

The display back section 10 is defined on its sides from the panel connecting sections 70 11 and 12 by the parallel longitudinal score lines 32 and 33 and is defined at its top from the top closure flap 15 by the transverse score line 34. The panel connecting sections 11 and 12 are defined from the panel sections 13 and 14 by the parallel longitudinal score lines 35 and 36. The panel sections 13 and 14 are free-hanging on the panel connecting sections for hinge movement and each panel section in width is one-half the width of the 75 display back section 10 for forming an inner cover when the container is in closed form. As shown the panel sections are rounded at their upper outer ends, but as may be readily understood, these outer upper ends may be 80 made rectangular if desired.

The pocket inner rear wall section 16 is a rigid extension of the section 10 and is not foldably connected thereto, but in Fig. 6 for purposes of description the section 16 is 85 shown as defined from the section 10 by the dot and dash line d, the width of the section 16 thus being shown as from the lines d to the transverse score line 37 whereby the section 16 is defined from the pocket bottom 90 section 19; the pocket inner rear wall section 16 is defined at its ends from the pocket inner end wall sections 17 and 18 by extensions of the score lines 32 and 33. The pocket inner 95 end wall sections 17 and 18 are free on one 100

side and one end and are rigid extensions of the panel connecting sections 11 and 12 and for purposes of description are indicated as defined therefrom by extensions of the line 5 *d*. The pocket bottom section 19 is defined from the pocket inner front wall section 22 by the transverse score line 38 and is defined at its ends from the pocket end closure tabs 20 and 21 by extensions of the score lines 32 and 33, these tabs being free-hanging on the section 19. The inner front wall section 22 is free on its ends and is defined from the pocket outer front wall section 23 by the transverse score line 39. The pocket outer front wall 10 section 23 is free on one of its sides and is defined at one end from the pocket outer end wall section 24 by a score line in extension of the score line 32, and is defined at its other end from the pocket outer end wall section 25 by a score line in extension of the score line 33. The pocket outer end wall section 24 is free on its ends and is defined from the pocket outer rear wall section 27 by a score line in extension of the score line 35. The 15 pocket outer end wall section 25 is free on its ends and is defined from the locking tab section 26 by a score line in extension of the score line 36. The pocket outer rear wall section 27 is free on one of its sides and has the locking tab 28 on one end and is defined from the brace section 29 by a score line in extension of the score line 39. The brace section 29 is free at its ends and is defined from the base section 30 by a score line in extension 20 of the score line 38. The base section 30 is free at its ends and is defined from the tuck 31 by the score line 41.

To form the container from the blank the bottom section 19 is folded upwardly on the score line 37 so that it is at a right angle to the inner rear wall section 16, the inner front wall section 22 is folded upwardly on the score line 38 to position at a right angle to the bottom section 19 and parallel to the inner rear wall section 16 and spaced away therefrom by the bottom section 19, the inner end wall sections 17 and 18, and the panel connecting sections 11 and 12, are folded inwardly on the score lines 32 and 33, the sections 17 and 18 being disposed in positions at right angles to and between the inner rear wall section 16 and the inner front wall section 22, the end closure tabs 20 and 21 are folded inwardly on the score lines 32 and 33 to lie flat against the inner end wall sections 17 and 18, the outer front wall section 23 is folded downwardly on the score line 39 to lie flat against the inner front wall section 22, the outer rear wall section 27 being folded downwardly on the score line in extension of the score line 39 and carried around rearwardly to lie flat against the inner rear wall section 16, the outer end wall section 24 being thereby folded on its score lines and caused to lie flat against the inner end wall

section 17, the tab 20 being disposed between these end walls, the outer end wall section 25 and locking flap section 26 are carried around rearwardly so that the outer end wall section 25 lies flat against the inner end wall section 18, the tab 21 being disposed between these end walls, and the locking flap section 26 is interlockably engaged with the locking flaps 28, the outer front wall section 23, outer end wall sections 24 and 25, outer rear wall section 27 and locking tabs 26 and 28 constituting a binder around the pocket portion of the container. The brace section 29 is folded downwardly on the score line in extension of the score line 39 to an inclined position, the base section 30 is folded inwardly on the score line in extension of the score line 38 and towards the outer rear wall section 27, and the tuck 31 is folded on the score line 41 and inserted in the space between the outer and inner rear wall sections 27 and 16. Articles, such as cartons XX, being placed in the pocket portion and extending above the upper edge thereof, a display container of substantially cabinet form such as shown in Fig. 1 is provided, the back 10, panels 13 and 14 when folded outwardly on the score lines 35 and 36 and the outer front wall 23 of the pocket providing space for placing advertising or characteristic matter thereon.

To form a closed container, Fig. 3, panels 13 and 14 are folded inwardly to lie in adjacent alignment at right-angles to the side connections 11 and 12 and form an inner cover for the display portion of the container, the flap 15 is folded downwardly on the score line 34 to form a closure at the top of the container, the tuck 31 is withdrawn from between walls 27 and 16 and the tuck 31, base 30 and brace 29 are disposed flat against the rear side of the display back 10, and an outer slip over cover 42, of well known form, Fig. 4, extending from the top of the closed display portion to the top edge of the pocket is disposed over the closed display portion and over the easel forming portions of the container.

When the container is in display condition a single tier of articles XX may be placed in the pocket, thus permitting a good view of advertising or other matter on the display section 10, a plurality of tiers of these articles being arranged in the container for filling it, as indicated in outline in Fig. 3, when the container is in closed form.

What I claim and desire to protect by Letters Patent is:

1. In a foldably formed container a display portion, a pocket forming portion, having thereon an inner rear wall section, which is continuous with said display section, a bottom section, foldably connected to said inner rear wall section, an inner front wall section, foldably connected to said bottom section, and an outer front wall section, foldably con-

nected to said inner front wall section, said display portion with said inner rear wall section having at the sides thereof a pair of panel connecting sections, foldably connect-
 5 thereto, and a pair of panels at the sides of said panel connecting sections, foldable to open free hanging positions, when the container is assembled for display, and foldable to closing position, when the container is in assembled closed form, combined with a pair of outer end wall sections, foldably connected to said outer front wall section, an outer rear wall section, adjacent to and foldably connected to one of said outer end wall sections, and an easel forming portion, fold-
 10 ably connected to said outer rear wall section, said easel to support said container, when assembled for display, and said easel portion being foldable, to lie flat against the rear of said container, when the latter is in assembled closed form, to permit a slip over cover to be drawn over the easel and the upper portion of the container in the assembled closed form of the latter.

25 2. In a foldably formed container the elements of claim 1, combined with a pair of inner end wall sections, foldably connected to said inner rear wall section, said outer end wall sections with said inner end wall sections forming double end walls for said pocket, said outer front wall section with said inner front wall section forming a double front wall for said pocket, said outer rear wall section with said inner rear wall section forming a double rear wall for said pocket, and the outer walls of said double walls forming a binder for retaining the container in assembled form.

30 3. In a foldably formed container the elements of claim 1, said easel portion includ-
 35 ing a brace section, foldably connected to said outer rear wall section, a base section, foldably connected to said brace section and an easel tuck, foldably connected to said base section, said brace section being folded, to extend downwardly to an inclined position, when said container is assembled for display, said base section being folded to extend inwardly from the foot of said brace section towards said outer rear wall section, to lie flat in a horizontal position, and said tuck being folded upwardly and inserted into the space between said outer and inner rear wall sections, thereby sustaining said container in position.

35 4. The blank for forming a container by folding the blank on score lines and cuts defining the sections thereof, said blank includ-
 40 ing a display back section, panel connecting sections, panel sections, a top closure flap on the display back section, a pocket inner rear wall section, a pocket bottom section, pocket end closure tabs, a pocket inner front wall section, a pocket outer front wall section, pocket outer end wall sections, a locking tab

section on one of said outer end wall sections, an outer rear wall section having a locking tab thereon, an easel brace section, an easel base section, and an easel tuck.

5. The blank for forming a container by folding the blank on score lines and cuts defining the sections thereof, said blank consisting of an oblong main portion having side extensions thereon and a smaller substantially square portion free-hanging on the main portion, said main portion including a display back section, a top closure flap on the display back section, a pocket inner rear wall section, a pocket bottom section, a pocket inner front wall section, and a pocket outer front wall section, said extensions including panel connecting sections, panel sections, pocket inner end wall sections, pocket end closure sections, and pocket outer end wall sections, said square portion being free-hanging on said main portion by one of said outer end wall sections and the other of said end wall sections having a locking tab thereon, said square portion including a pocket outer rear wall section having a locking tab thereon, an easel brace section, an easel base section and an easel tuck.

Signed at New York, in the county of New York and State of New York, this 27th day of November, 1927, A. D.
